UNITED STATES PATENT OFFICE.

EDWARD HUBER, OF MARION, OHIO.

CENTRIFUGAL GOVERNOR.

SPECIFICATION forming part of Letters Patent No. 553,852, dated February 4, 1896.

Application filed May 14, 1895. Serial No. 549,307. (No model.)

To all whom it may concern:

Be it known that I, EDWARD HUBER, of Marion, in the county of Marion and State of Ohio, have invented certain new and useful 5 Improvements in Centrifugal Governors; and I do hereby declare the following to be a full, clear, and exact description of the invention, such as will enable others skilled in the art to which it appertains to make and use the same.

10 My invention relates to an improvement in centrifugal governors, and is designed more particularly for controlling the operation of self-feeders for thrashing-machines, the object of the invention being to produce a simple and efficient governor which shall be so constructed and arranged that the mechanism to be operated will be automatically thrown into action when the driven pulley shall have attained a certain predetermined rate of 15 speed and so that said mechanism will be automatically thrown out of action when the speed of the driven pulley decreases below the predetermined rate.

With this object in view the invention consists in certain novel features of construction and combinations and arrangements of parts, as hereinafter set forth, and pointed out in the claim.

In the accompanying drawings, Figure 1 is 20 a sectional view illustrating my improvements. Fig. 2 is a face view with the fast pulley removed.

A represents a shaft, on which a pulley B is loosely mounted and adapted for the reception of a suitable strap from any convenient 25 source of power and by which said loose pulley B will be driven. A pulley C is keyed to the shaft A in close proximity to the pulley B and provided with a laterally-projecting 30 peripheral flange a. Weighted arms C' C'' are pivotally connected at one end with arms b of the pulley B at points in proximity to the outer ends of the latter. To each weighted arm, at a point in proximity to its pivotal connection with the pulley B, a pintle c is secured and projects laterally therefrom. To each pintle c a shoe D is loosely connected and adapted, when the weighted arms C' swing 35 outwardly, to engage the inner face of the pe-

ripheral flange a on the pulley or disk C. Each 50 weighted arm C' is provided, at a point between its ends, with a perforated ear d for the attachment thereto of a rod e, which latter also passes through a guide f on an arm of the pulley B and extends some distance beyond said guide. The free end of each rod e is screw-threaded for the reception of a nut g, and located on each rod between the guide f and nut g is a spring h, the tension of which can be regulated by means of the nut g. The 55 nuts g will be adjusted in such manner as to cause the springs h to offer sufficient resistance to the movement of the weighted arms C' to prevent the engagement of the shoes D with the flange a of the pulley or disk C until 60 the driven pulley B shall have reached a certain predetermined rate of speed. When the driven pulley B reaches the desired rate of speed the weighted arms C' will be thrown out by centrifugal force and the shoes made 65 to engage the peripheral flange a of the disk or pulley C, thus, in effect, locking the driven pulley B to the shaft A and causing the latter to rotate to drive the machinery connected with it. When the speed of the pulley B decreases below the predetermined rate, the 70 springs h will serve to withdraw the weighted arms C' and the shoes carried thereby, and thus unlock or throw the machinery out of 75 action.

It will thus be seen that the machinery connected with the shaft A will only be actuated when the pulley B reaches a certain predetermined speed, thus rendering the device valuable for controlling or governing the self-feeder of a thrashing-machine.

Having fully described my invention, what I claim as new, and desire to secure by Letters Patent, is—

The combination with a shaft, a pulley 90 loosely mounted thereon, and a pulley keyed thereon and provided with a laterally-projecting annular flange extending toward and in close proximity to the loose pulley, of weighted arms pivoted to the spokes of the 95 loose pulley, shoes pivotally connected with these weighted arms near their pivots, and adapted to bear on the flange of the other

pulley, a rod extending from each weighted arm and having sliding connection with spokes of the loose pulley, a spiral spring on each rod outside of its point of connection
5 with the spoke of the loose pulley and means for regulating the tension of these springs, substantially as set forth.

In testimony whereof I have signed this specification in the presence of two subscribing witnesses.

EDWARD HUBER.
